Term of patent 14 years

(Cl. D58—26)

FIG. 1

FIG. 3

FIG. 2

FIG. 1 is a perspective view of a combined container closure and measuring spoon, showing my new design; FIG. 2 is a bottom plan view; and

FIG. 3 is a side elevational view thereof.

The broken line showing of a portion of a container in FIG. 1 is for illustrative purposes only.

I claim:

The ornamental design for a combined container closure and measuring spoon, as shown and described.
